UNITED STATES PATENT OFFICE

140,932

DESIGN FOR A SEWING MACHINE VISE

Max Ingwer, New York, N. Y., assignor to Consolidated Sewing Machine & Supply Co., Inc., New York, N. Y., a corporation of New York

Application December 29, 1944, Serial No. 117,153

Term of patent 14 years

(Cl. D54—14)

To all whom it may concern:

Be it known that I, Max Ingwer, a citizen of the United States, residing at New York, in the county and State of New York, have invented a new, original, and ornamental Design for a Sewing Machine Vise, of which the following is a specification, reference being had to the accompanying drawing, forming part thereof.

Fig. 1 is a top plan view of a sewing machine vise embodying my new design;

Fig. 2 is a side elevation of the same; Figs. 3 and 4 are front and back views of the same.

I claim:

The ornamental design for a sewing machine vise, substantially as shown.

MAX INGWER.
